UNITED STATES PATENT OFFICE

2,193,572

ELECTRIC LAMP

Kenneth P. Swanson, Rockport, Mass., assignor,
by mesne assignments, to Birdseye Electric
Corporation, Gloucester, Mass., a corporation
of Massachusetts

Application May 17, 1938, Serial No. 208,412

12 Claims. (Cl. 176—38)

The present invention relates to electric incandescent lamps and consists in an improved filament supporting structure for use in lamps of high wattage, more particularly in those in which the filament is positioned at a considerable distance from the base. In lamps of this type one serious cause of deterioration has been found to be relative movement or vibration of the lead or supporting wires which causes breaking of the filament. Furthermore, the usual practice has been to seal the lead and supporting wires into the press, and it often happens that vibration of the structure above the press causes the stem or flare of the mount to break, especially during handling and shipment of the lamp. With a view to improving these conditions it is proposed in accordance with this invention to bind the lead and supporting wires into a group to prevent relative vibration thereof and also to provide means outside the press and the stem of the mount but cooperating therewith to anchor the lead and supporting wires and relieve the press and the mount from harmful stress.

An important feature of the invention as herein shown resides in the novel structure used for holding the filament in position at the ends of the supporting wires, a structure which is particularly advantageous when used in combination with coiled or coiled coil filaments and designed to allow expansion and contraction of the filament without undue stress thereon.

A further feature of the invention lies in the utilization of two of the supporting wires as supplementary or extension lead-in wires in conjunction with leads of the usual type sealed in the press, thereby reducing the weight of the filament supporting structure.

These and other features of the invention will be best understood and appreciated from the following description of a preferred embodiment thereof, selected for purposes of illustration and shown in the accompanying drawing, in which:

Fig. 1 is a view in side elevation of a filament support constructed according to the invention.

Fig. 2 is a view in side elevation taken at right angles to Fig. 1.

Fig. 3 is a view taken along the line 3—3 of Fig. 1.

Fig. 4 is a view taken along the line 4—4 of Fig. 1.

Fig. 5 is a plan view of the filament, and

Fig. 6 is a view in cross section taken along the line 6—6 of Fig. 5.

In Fig. 1 is shown part of a glass lamp bulb 10 having a neck and a conventional metal base 11 threaded to fit a lamp socket. A hollow tubular flare or stem 12 fused in the neck of the bulb 10 contains an exhaust tube 14 and the lower portions of two lead wires 15 and 16. Above the end of the exhaust tube 14 the stem 12 ter-

minates in a flattened solid press 13 into which the lead wires 15 and 16 are sealed, and a sturdy cylindrical glass rod or arbor 17, integrally formed with the press 13, projects upwardly therefrom.

Midway of the hollow stem 12 is placed a flat spreader disk or anchor plate 18 of insulating refractory material, such as mica, and this is provided with a central aperture to fit the stem 12 and, in the illustrated construction, with six pairs of eyelets 20 disposed at spaced intervals about its circumference. Two stiff wires 21 and 22 are welded or otherwise secured to the upper ends of the lead wires 15 and 16 and are anchored longitudinally in the lamp in adjacent pairs of eyelets 20 in the disk 18; the wires 21 and 22 thus serve as supplementary lead wires when connected to the end of a filament 27. Four supporting wires 23 are also anchored in the disk 18 by being hooked into eyelets therein 20 and project longitudinally into the interior of the lamp 10 in spaced relation with the supplementary lead wires 21 and 22.

Fitted over the glass arbor 17 is a second perforated spreader disk 24 formed of insulating material and greater in circumference than the disk 18 but spaced well within the flaring walls of the bulb 10. Six eyelets 26 are spaced around the margin of the disk 24 for the accommodation of the wires 21, 22, and 23 as shown in Fig. 3 and two similar eyelets are placed adjacent the rod 17 to serve as passages for the leads 15 and 16. Since the disk 24 is larger in circumference than the anchoring disk 18, the wires 21, 22, and 23 are spread out in passing through it. Longitudinal movement of the disks and the wires is prevented by the connection with the lead wires 15 and 16 which are sealed in the press 13. The wires and disks form a light, stiff truss frame.

Tungsten wire loops or "pigtails" 28 are welded at one end to the upper ends of each of the wires 23 as shown clearly in Fig. 6, and inclined tungsten braces 29 are welded to the outer ends of the loops 28 and to the wires 23 below the ends thereof. A coiled coil filament 27 of tungsten wire arranged in a hexagonal pattern rests within the bight of the braced loops 28 and is clamped at its ends by hooks bent in the upper ends of the supplementary lead wires 21 and 22, as shown in Fig. 5. The disks 18 and 24 support and bind the filament supporting wires 23 as well as the supplementary lead wires 21 and 22 with the result that the whole mount acts as a self-contained unit to withstand the shocks occurring during shipment and handling. The danger of breaking the flare or stem of the mount is considerably alleviated, since the filament supporting wires are anchored outside it. Moreover, this construction obviates the necessity of using special hard glass for the flare or stem because sub-

stantially all the glass structure of the mount is located below the insulating disk 24. It will be apparent that the disks and the wires form a light truss frame guided on the mount and the 5 glass rod and held against longitudinal movement by the short lead in wires sealed in the press. In assembling the mount in the lamp however, its position and consequently the position of the filament in the lamp may be adjusted 10 accurately before spot welding the lead wires 15 and 16 to the upright supporting wires 21 and 22.

It will be understood that the truss frame of my invention is useful in any type of electric lamp but that its special field of use is in gas 15 filled lamps in 750, 1,000 and 1,500 watt sizes or in even larger sizes.

The details and features illustrated comprise one good practical form of the invention, but it is to be understood that these may be varied 20 in form, location and arrangement and still be within the scope of the invention as set forth in the appended claims which define what I claim as new and desire to secure by Letters Patent of the United States.

25 I claim:

1. In an incandescent electric lamp having a bulb and a hollow stem therein, a light stiff truss frame having a pair of spreaders centered on the mount, longitudinal members connected to the 30 spreaders, means for carrying the weight of the truss frame, and a filament carried by the longitudinal members thereof.

2. In an incandescent electric lamp having a bulb and a hollow stem therein, a light stiff truss 35 frame having a pair of spreader disks centered on the mount, longitudinal wires spaced by connection with said disks, means engaging certain of said wires to carry the weight of the truss frame, and a filament supported at the ends of 40 the wires.

3. A gas filled electric lamp of more than 1000 watt rating including in its structure a bulb having therein a hollow stem terminating in a projecting arbor, a light stiff truss frame having a 45 disk centered on the mount, a larger disk centered on the arbor and longitudinal wires spaced and supported by said disks, wires sealed in the press and connected to wires of the frame for supporting the same, and a coiled tungsten filament supported by the wires of the truss frame.

4. In an electric incandescent lamp including in its structure a bulb having a stem in its neck, a light stiff truss frame for supporting a filament, said frame comprising spaced disks disposed coaxially with respect to the stem and longitudinal wires shaped and supported by said disks, at least one of said disks being held against transverse movement by engaging said stem.

5. In an incandescent electric lamp including 50 in its structure a bulb having a neck, and containing a tubular stem, a truss frame for supporting a filament, said frame including a lower disk centered upon the mount and spaced at its periphery within the neck, an upper larger disk 55 spaced at its periphery from the walls of the bulb, a series of longitudinal wires anchored in the lower disk and extending upwardly in evenly spaced relation through said upper disk, and means for supporting the weight of the truss frame independently of said lower disk.

6. A filament support for an incandescent elec-

tric lamp which comprises a stem, an anchor plate surrounding said stem and formed of insulating material, lead wires projecting from said stem, a glass rod integral with said stem and projecting upwardly therefrom, a plurality of supporting wires fast in said anchor plate, a filament held in position by said support wires, said lead wires being secured to two of said support wires, and a spreader on said glass rod provided with spaced holes through which said supporting wires pass.

7. A filament support for electric incandescent lamps, which comprises a stem and integral press, an anchor plate disposed around said stem, a plurality of supporting wires caught in said anchor plate, a filament held by said supporting wires, lead wires connected to two of said supporting wires, and an insulating spreader disk spaced from said anchor plate and provided with 15 passages for the supporting and lead wires. 20

8. A filament mount for electric incandescent lamps, which comprises a stem, lead wires projecting therefrom, a plurality of supporting wires anchored outside said stem, two of said supporting wires being secured to said lead wires, wire 25 loops secured to the upper ends of each of the other support wires, bracing wires secured to said supporting wires and to said loops, a filament supported in said loops and connected to the first two supporting wires, and an insulating 30 spreader disk provided with passages for said supporting wires.

9. In an incandescent electric lamp having a bulb and a base, filament supporting means including a stem having a press at its inner end, 35 lead wires projecting from said press, an arbor also projecting from said press, an insulating anchor disk disposed around said stem, a plurality of supporting wires hooked in said anchor disk, a spreader disk disposed around said arbor and 40 provided with eyelets forming passages for said lead and supporting wires, braced wire loops on the upper ends of said supporting wires, and a coiled coil filament held in said wire loops.

10. A filament support which comprises a 45 length of stiff wire having a hook at one of its ends, a wire loop secured at one end to said length of wire, and a stiff bracing wire connected to said wire loop and to said length of wire.

11. A filament support for electric incandescent 50 lamps, which comprises a tubular glass stem, an anchoring disk perforated to fit upon said stem, a plurality of supporting wires secured to said anchoring disk, a spreader disk spaced from said anchoring disk and provided with passages for 55 said supporting wires which are extended beyond the spreader disk and beyond the end of the stem, and means on the upper ends of said supporting wires for retaining a filament.

12. An electric lamp having an internal tubular glass stem, a base, and a self-sustained filament-supporting structure comprising a pair of flat spacers mounted on the stem above the base and a plurality of wires spaced symmetrically about the spacers and maintained in position by 65 them, forming an open skeleton frame and extending beyond the same, and a filament supported by said wires beyond the end of the stem and connected in electrical circuit with two of 70 said wires.

CERTIFICATE OF CORRECTION.

Patent No. 2,193,572.

March 12, 1940.

KENNETH P. SWANSON.

It is hereby certified that error appears in the printed specification of the above numbered patent requiring correction as follows: Page 2, first column, lines 29 and 36, claims 1 and 2 respectively, for the word "mount" read stem; and that the said Letters Patent should be read with this correction therein that the same may conform to the record of the case in the Patent Office.

Signed and sealed this 16th day of April, A. D. 1940.
